UNITED STATES PATENT OFFICE.

WILLIAM F. LAUTENSCHLAGER, OF CINCINNATI, OHIO, ASSIGNOR TO LORENZ MUTHER, OF DENVER, COLORADO.

EYELETING-MACHINE.

No. 926,948.

Specification of Letters Patent.

Patented July 6, 1909.

Application filed March 5, 1906. Serial No. 304,304.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Eyeleting-Machines, of which the following is a specification.

My invention relates to eyeleting machines employing a punch for cutting away part of the goods for forming a hole therein for the ready reception of the eyelet in such manner that the goods about the eyelet may not be bunched after the eyelet has been set by the coöperating setting dies, and is especially applicable in the manufacture of shoes or other leather goods or goods in which it is desirable to punch a preparatory hole for the eyelet by the removal of material by means of a ring or eyelet punch.

It is the object of my invention to provide new and useful improvements in eyeleting machines, whereby the objections in eyeleting machines as heretofore constructed are overcome, the said objections relating to the manner of mounting and setting the eyelets, especially where imperfect eyelets are encountered, and it is the further object of my invention to provide new and improved means for accurately centering and sustaining the eyelet with relation to the punching or setting devices and to the goods being eyeleted as well as for accurately centering and sustaining the coöperating setting tools with relation to each other.

Instancing the objections mentioned as the same are present in one type of eyeleting machine in use, this type of machine employs a punch which serves as a member of the coöperating setting dies, the punch, while operating as one of the coöperating setting dies, being intended to take inside of the barrel of the eyelet for spreading said barrel, the eyelet, preparatory to such spreading operation, being mounted upon the opposing setting die, there also being a spring-pressed finger reciprocable in said last-mentioned setting die adapted to receive the eyelet from the eyelet-chute or runway, the said finger having recession with relation to the punch setting-die when the latter performs its setting operation, the eyelet also, just prior to the setting operation, being without central guidance for

definitely positioning the eyelet with relation to the punch setting-die. The eyelet is therefore permitted to wabble upon the opposing setting die with the result that when the approach between the eyelet and the punch setting-die takes place, the punch setting-die will often not be received within the barrel of the eyelet as intended but often makes contact with the outer edge of the eyelet-barrel, thereby destroying the eyelet and almost invariably damaging and often breaking the eyelet-punch and damaging the work, and causing stoppage of the machine for renewal of the parts. This vibration, wabbling and uncertainty of guidance of the eyelet is incident to the machines of various types of the general character mentioned, now in general use, and when it is taken into consideration that these machines are operated very rapidly, and that the eyelet is very light, it will be noted that the vibrations caused by such rapid operations in a machine of this character are communicated to the eyelet, causing uncertainty in its placement at the time the setting operation is performed.

In other types of machines in quite general use the finger is adapted to make end to end contact with the opposing setting die, which in practice however occurs in imperfect alignment with relation to each other, owing to vibration of the machine and lost motion, also permitting lateral movement of the eyelet in its relation to the opposing setting die in such manner as to often cause buckling or inward crimping instead of outward spreading of the barrel end of the eyelet. These objections are serious in the practical operation of the machines and result in material loss of stock operated upon as well as loss of eyelets and in breakages in the machines and consequent delays; and imperfections in eyeleting work are especially objectionable when it is considered that imperfections in a single eyelet may destroy the usefulness of an entire piece of stock.

It is the object therefore of my improved device to avoid the objections stated, and my invention consists in providing coöperating setting dies in a machine of the character mentioned, one of which setting dies has therein an eyelet-receiving finger having an enlargement thereon adapted to receive the eyelet

for guiding the same, the other of said dies having a central bore adapted to receive the shank of said finger for positioning the said shank with relation to both said dies; further in providing said shank of said finger with a reducing end for being readily received by the opposing die and with a shoulder at said enlargement with which the end of said opposing die is adapted to engage preparatory to the setting operation for forming a guiding and setting face without obstruction against which the eyelet may either receive or impart injury; further in constructing said enlargement so as to project from its die slightly more than the distance which said barrel projects beyond the eyelet for locating said shoulder beyond the eyelet when seated for causing said opposing setting die to make engagement with said shoulder prior to engagement with said eyelet; further in providing a punch-setting-die with a bore of enlarged diameter adjacent to its cutting edge, *i. e.* larger than the bore of said punch at its cutting edge, for forming clearance for the ready release of the punchings of said cutter or punch, and in so associating said improvements and operating mechanism therefor as to cause proper relation and contact between the parts for forming the setting or the punching and setting functions, and further in the parts, and in the construction, arrangements and combinations of parts hereinafter more fully described and claimed.

In the drawings: Figure 1 is a front elevation of an exemplifying machine embodying my invention. Fig. 2 is a cross section of the same on the irregular line $x-x$ of Fig. 3. Fig. 3 is a central vertical longitudinal section of the same. Fig. 4 is a detail in section on the line $y-y$ of Fig. 3. Fig. 5 is a side elevation of the setting-die with the eyelet finger therein. Figs. 6, 7, 8, 9 and 10, are sectional details illustrating the successive steps in the operation of my improved device; and, Fig. 11 is a sectional detail illustrating the operation of my improved device in connection with a separate punch for performing the punching operation, it being understood that the punch and the members of the setting-dies have relative cross-reciprocation imparted thereto by suitable mechanism.

1 represents the frame of the machine, on which a head 2 has lateral reciprocation on rods 3, a bar 4 having up and down reciprocation upon said head.

5 is a table or anvil on which the stock is adapted to be fed and 6 is a bar adapted to have up-and-down reciprocation imparted thereto under the table.

7 is a pressure-foot arranged to take against the stock on the table, said stock being shown in the drawings at 8.

9 is a punch mounted in the bar 4 and in the present exemplification of my invention,

this punch also serves as a member of the coöperating setting-dies, the other member of said coöperating setting-dies being shown at 10 mounted on the bar 6, the said punch and setting-dies being hereinafter more fully described.

11 is an eyelet feed-chute for the eyelets 12 and having a hopper 13 adapted to contain the eyelets, from which the eyelets are fed into the feed-chute into proximity with the setting dies. The chute has motion imparted into and out of the path of said setting-dies in ordinary manner so as to present the eyelets one after the other to the finger 14.

15 is a driving shaft operated in suitable manner and arranged to reciprocate the bar 6 up and down as by being provided with a crank 16 having a crank-pin 17 journaled in a block 18 having cross-reciprocation in a slideway 19 of a collar 20 secured to the bar 6. The shaft 15 also carries a cam 21 having engagement with contact faces 22 of a rocking frame 23 having an extension 24 connected with an arm 25 of a sleeve 26, rocking upon a shaft 27. The connection between the extension 24 and the arm 25 is preferably adjustable with relation to the oscillating axis of the sleeve 26 by having a stud 28 adjustably positioned in an arc-slot 29 in the arm 25. The sleeve 26 has a lug 30, and a collar 31 having an arm 32 takes about said sleeve and is readily adjustable with relation thereto by means of adjusting screws 33. The said arm 32 has a slideway 34 extending radially thereof in which a block 35 has movement, a pin 36 being secured to the head 2 and journaled in said block for translating the rocking movement of said sleeve 26 into laterally reciprocating motion of said head. In order to further govern the length of cross-reciprocation of the head, a bell-crank lever 37 rocking on a pin 38 and articulated with said extension 24 by means of a link 39 is provided, screws 40 having jam-nuts 41 limiting the movement of said bell-crank lever, which is adapted to be set in motion by a connection 42 operated from a treadle or other suitable lever. The shaft 15 also carries a cam 43 having engagement with contact faces 44 of a rocking-frame 45 on an arm 46 pivoted at 47 to the main frame and provided at its other or swinging end with a segmental rack 48 engaging a segment 49 on shaft 27 for rocking the latter, the said shaft having an eccentric 50 journaled in a block 51 upon which a slide 52 is supported and by which said slide is moved, said slide being adjustably secured to the bar 4 by means of set-nuts 53.

The pressure-foot 7 is mounted on a rod 54 adapted to be reciprocated by a lever 55 pivoted at 56 to the main frame and automatically operated by a cam 57, the said pressure-foot also arranged to be operated 130

by a lever 58 pivoted to the frame and connected with a foot-treadle or other operating device.

The eyelet-chute 11 is shown as operated 5 by means of a lever 60 having a yoke 61 taking about the cam 57 and connecting with said chute for oscillating the same.

As thus far described, the machine operates, broadly stated, as follows: Stock being 10 placed upon the table under the pressure- foot, the bar 4 is caused to descend for causing the punch 9 to pierce the goods against the anvil or table 5, and immediately has a slight rise imparted thereto for relieving 15 its contact with said anvil for permitting cross-reciprocation of the punch without injury to the anvil or punch and for bringing such punch into longitudinal plane with the setting die 10 for performing the setting operation. In such cross-reciprocation shoes 20 62 make contact with the lower side of the goods for forcing the goods upon the punch, the operation being substantially as more fully shown and described in Letters Patent 25 No. 686,928, granted P. R. Glass, November 19, 1901. The bar 6 is preferably hollow and has a rod 63 adjustable therein making contact with a shell 64 upon which the setting die 10 is supported, the setting-die 10 30 being secured to said bar by a socket-nut 65. The finger 14 is slideable in the setting die 10 and is normally held in upward position by means of a spring 66 taking against a heel 67, which serves as a stop for limiting the upward 35 movement of the finger. The setting die 10 has a setting face 68, and said finger at said setting face is of a diameter coinciding substantially with the diameter of the eyelet which is arranged to be received about 40 the finger, forming an eyelet-guide 69, which is of a length equal to or preferably slightly longer than the height of the eyelet above said setting-face and ending in a shoulder 70 between it and the reduced shank 71 of the 45 finger, the said reduced shank terminating in a reduced end 72 for purposes presently to be explained. Eyelets usually have a tapering barrel and I prefer to taper the guide 69 as shown. The punch 9 has an 50 annular cutting web 73 having a cutting edge 74 adapted to form the hole in the goods which is subsequently to receive the eyelet. In the exemplification of machine shown, the goods, such as leather, after 55 being punched, is transversely fed by means of the punch, and forced upwardly upon the cutting web. The punch 9 forms one of the co-operating members of the setting dies, and the part 9 may form one of such co-operating 60 members irrespective of whether or not it is employed to perform the function of a punch.

In setting the eyelet, the eyelet having 65 been received upon the finger 14, and consequently taking about the eyelet-guide 69,

motion is imparted to the parts for first causing relative approach between the co-operating setting dies for seating the cutting edge 74 upon the shoulder 70. It will further be noted that the reduced end 72 of the finger will readily find the bore 75 in the punching die 9, so as to prevent end contact between said end of said finger and the said die, irrespective of irregularities or vibration of the parts or lost motion in the machine, the said reduced shank 71 of the finger thereupon finding ready seat within the said bore and causing accurate relative longitudinal and lateral setting between the co-operating setting dies. The said edge 74 having 75 found seat upon the shoulder 70, and the diameter of the edge 74 being at least as small as the diameter of the shoulder 70, a substantially continuous guiding and setting face is formed against which the barrel end 80 of the eyelet may be forced without meeting with obstruction or disfigurement, the web 73 being made flaring away from its outer end in ordinary manner for a setting die. The shoulder 70 is preferably a flat shoulder 85 against which the cutting edge 74 is adapted to make flat contact, thereby preventing injury to the cutting edge and preventing its burring or flaring as would be the case if said cutting edge were caused to take against 90 a slanting or curved surface. The said cutting edge is also preferably of slightly less diameter than said shoulder. After seat has been made between said end or cutting edge and the shoulder 70, further relative 95 movement between the setting dies is caused for forcing the eyelet-barrel through the goods and for flaring the outer end of said barrel for setting the eyelet into the goods, the punched hole, in the present 100 exemplification, being of less diameter than the outside diameter of the eyelet.

The exemplification shown in Fig. 11, shows my improved device applied when a separate punch is employed. 76 is a separate 110 punch. 9' is the setting die provided with a bore 75' into which the reduced shank 71' of the finger 14' is adapted to take, the finger 14' taking through an opposing setting die 10'. The said finger is backed by a spring, 115 not shown but similar to the spring 66, and provided with an eyelet-guide 69' terminating in a shoulder 70', the reduced shank terminating in a reducing outer end 72'. The engaging face 74', or extreme end or eyelet-guide on the die 9' is adapted to make engagement with said shoulder 70', prior to the relative movement between said finger and eyelet, whereupon the finger is moved by its opposing die and engagement with the 120 barrel of the eyelet immediately transferred from said eyelet-guide on said finger to the eyelet-guide formed by web 73' on said opposing setting die 9', the parts also continually maintaining lateral support between 125

said finger and both said dies for sustaining the dies in centered relation irrespective of vibrations or lost motion. When said die 9 is used as a punch I enlarge the bore 75 adjacent to its cutting edge, for forming an enlarged bore 77, which I have shown as tapering or flaring. The object of this is to provide ready release of the punchings 2 in the bores made by the cutting operation, so that 10 the shank of the finger may have ready entrance into the bore of the punch when the latter is used as a punch and for permitting the finger and its setting die to remain relatively stationary until the seating of the 15 punch edge or face upon the shoulder 70. The punchings are discharged through a passage 78 having an opening 79 in the bar 4.

In my improved construction further, the eyelet has seat upon a central eyelet-guide 20 which is stationary with relation thereto until the eyelet-guide of the opposing setting die is in close juxtaposition thereto, the reduced shank of said finger having meanwhile entered said opposing setting die, thereby 25 insuring that the eyelet and the coöperating setting dies shall be centered and laterally supported all with relation to each other prior to the beginning of the actual setting operation, thereby nullifying the results of, 30 vibration and lost motion in the machine, and permitting exceedingly rapid operation and excellence of workmanship with minimum loss of material.

Having thus fully described my invention 35 what I claim as new and desire to secure by Letters Patent is:

1. The combination, in a machine of the character described, of a pair of coöperating setting-dies, one of said setting-dies having 40 an eyelet-seat thereon, and an eyelet-receiving finger encompassed by said eyelet-seat and having an eyelet-fitting end normally projecting outwardly therefrom for a distance corresponding to the height of the eyelets, means for permitting relative longitudinal movement between said finger and last-named setting-die, said normally projecting eyelet-fitting end of said finger having a shoulder thereon at its outer extremity, 45 means for limiting the outward movement of said normally projecting end for locating said shoulder at substantially the location of the outer ends of the eyelets received by said finger when said eyelets are on said eyelet-seat, said finger and the setting-die opposed thereto having between them a shank beyond said shoulder and a bore therefor, said shank having a reduced end for being readily received in said bore and the sides of said 50 shank fitting said bore, said last-named setting-die having an engaging part thereon arranged for engagement with said shoulder, 55 and said engaging-part being of a diameter as small as the diameter of said shoulder, substantially as described. 65
2. In an eyeletting machine, the combination of a pair of coöperating setting-dies, a finger encompassed by one of said setting-dies and having an eyelet-fitting end normally protruding from said setting-die, means 70 for limiting the protrusion of said finger from said setting-die to a distance substantially equal to the height of the eyelets being set, said finger provided with an annular shoulder at the outer extremity of said eyelet-fitting end thereof, said normally protruding end fitting the bore of the eyelets and said shoulder being located at the outer end of said eyelets when said eyelets are located on said last-named setting-die, said finger provided with a reduced shank and the other of said setting-dies provided with a setting-face encompassing a bore fitting said shank, and said setting-face being of as small diameter as the diameter of said shoulder, 75 80 and operating substantially as described.
3. The combination, in a machine of the character described, of a punch setting-die having a bore and provided with a cutting edge merging into a setting face, a second 90 setting-die cooperating with said punch setting-die and having an eyelet-seat thereon, and an eyelet-receiving finger encompassed by said eyelet-seat, said finger having an eyelet-fitting end protruding from said eyelet-seat and provided with an annular shoulder at the outer extremity of said eyelet-fitting end thereof, means for limiting the protrusion of said eyelet-fitting end of said finger and said shoulder for normally positioning 100 said eyelet-fitting end for fitting the bores of the eyelets when located on said eyelet-seat and normally locating said shoulder at the upper ends of said eyelets when located on said eyelet-seat, said finger provided with a 105 shank above said shoulder, said shank terminating in a reduced end for being readily received by said first-named bore, the body of said shank fitting said first-named bore, said finger and second-named setting-die having 110 relative yielding movement between them upon engagement between said shoulder and said cutting-edge of said punch setting-die, and said cutting-edge being of as small diameter as the diameter of said shoulder, substantially as described. 115

In testimony whereof I have subscribed my name hereto in the presence of two subscribing witnesses.
